SELF-THREADING SHUTTLE

Application filed January 15, 1929. Serial No. 332,658.

This invention relates to self-threading shuttles and it is the general object of the invention to provide a shuttle of this type which will offer more resistance or tension to the 5 passage of the thread in the normal direction than is offered to the thread when moving in the reverse direction.

In weft replenishing looms operating with fine filling such, for instance, as silk or rayon 10 it is desirable to create a tension on the filling the first pick after transfer. Also, at the time of transfer the weft end which extends from the outgoing bobbin back to the selvage is withdrawn in a reverse direction through 15 the shuttle eye, but is subjected to the same tension as that operating during normal weaving. The effect of this is to retard or break the weft end of the outgoing bobbin so that a portion of filling remains in the box to 20 be whipped by the shuttle in the shed to cause an imperfection of the cloth. It is an important object of my present invention to provide a shuttle tension operative on the first pick of the loom to establish normal or relatively high tension but which will be effective 25 at the time of transfer to exert a reduced tension on the filling when the latter is being drawn in a reverse direction through the shuttle eye due to the movement of the outgoing 30 bobbin.

It is a more particular object of my present invention to provide a substantially fixed post with respect to the shuttle and to have the same engaged by a tension member movable 35 about a pivot so placed that the movement of the weft in the normal direction tends to draw the tension member against the post due to the location of the pivot of said tensioning member. It is a still further object of my present invention to arrange the previously 40 mentioned post and tensioning member so that when the weft is drawn in the reverse direction through the eye the natural effect 45 of the movement of the filling will be to move the tension member away from the post to reduce the tension.

With these and other objects in view which will appear as the description proceeds, my 50 invention resides in the combination and ar-

rangement of parts hereinafter described and set forth in the claims.

In the accompanying drawings wherein a convenient embodiment of my invention is set forth,

Fig. 1 is a top plan view of a shuttle having my invention applied thereto,

Fig. 2 is an enlarged top plan view of a portion of Fig. 1, the shuttle in both of these views being threaded to pay off yarn in the 60 normal or forward direction,

Fig. 3 is a front elevation taken in the direction of arrow 3, Fig. 1 on an enlarged scale,

Figs. 4 and 5 are vertical sections on lines 4-4 and 5-5, respectively, of Fig. 3, and

Figs. 6 and 7 are diagrammatic views showing the relation of my invention when the thread is moving in normal and reversed direction, respectively.

Referring to the drawings I have shown 70 the shuttle S having at the left hand end as viewed in Fig. 1 the usual spring clips 10 which receive the rings 11 of the butt 12 of a weft replenishing bobbin B. One wall of the shuttle may, if desired, be lined with fur as indicated at 13 to exert friction on the weft as the latter is unwound from the bobbin. At the opposite end of the shuttle is located the eye designated generally at E, said eye having a thread passage 14 which extends 75 generally in the direction of the length of the shuttle.

The eye is provided with an upstanding post 15 which may be secured to the floor 16 of the eye. Said post may have a conical upwardly facing end 17 as shown clearly in Fig. 4. A stud 18 may also be secured in the floor 16 and extend upwardly substantially parallel to the post 15.

As shown clearly in Fig. 2 the post 15 and stud 18 lie at different points along the path traversed by the filling W and this is an important feature of my present invention. As shown herein the stud 18 lies beyond post 15 with reference to the path normally traversed by the weft, and also lies rearwardly of the post 15. A yielding member 19 is coiled around the lower portion of the stud 18 and has a horizontal arm 20 which terminates in an upstanding tensioning element 21. The 100

latter, as shown clearly in Fig. 4, may have the upper end thereof bent away from the conical end of the post as at 22 so as to define with the end 17 an upwardly flaring notch 23 to receive the weft.

The delivery eye 24 as shown in Fig. 3 may be secured to the shuttle in any approved manner and has an opening 25 through which the weft W may extend and trail along a groove 26 formed in the front wall of the shuttle.

The tensioning element 21 is normally held yieldingly against the post 15 by means of a light spring 27 one end of which extends into an opening 28 in the vertical wall 29 of the eye as shown in Fig. 4, and the other end of which has engagement with a second diagonal extension 30 of the member 19. The spring and member 19 are so related that the tensioning element 21 normally lies against the post 15, said tensioning element being preferably in engagement with the post at a point slightly beyond the axis of the post with respect to the normal path traversed by the filling W.

The eye E of the shuttle is provided with a pair of threaders 31 and 32 which extend diagonally in opposite directions, one of these elements overlapping the other. An opening 33 is formed below the threaders in the left hand wall as viewed in Figs. 2 and 3 of the eye E for the reception of the filling W. The upper right hand portion of the eye as shown in Fig. 2 may be provided with beaks 34 and 35 which cooperate to deflect the filling downwardly on the first pick of the loom after transfer. The threading elements 31 and 32 together with the deflecting beaks 34 and 35 may be of the usual construction and are shown herein simply as effective means for directing the filling so that it will enter the previously described upwardly flaring notch 23.

At the time of transfer the filling will extend across the threading elements 31 and 32 and also the beak 34. During the first flight of the shuttle after transfer the weft will move downwardly into the opening 33 and will also move under the beak 35, extending throughout the first flight in a substantially straight line from the bobbin B across the right end of the shuttle toward the right selvage of the cloth being woven. During this first flight the weft will move downwardly between the end tension element 21 and the conical point 17 of the post 15 and will move in the direction indicated by arrow N in Fig. 6. Because of the location of the pivot for the tensioning member or element 21 the latter will be drawn toward the post by the filling by a force acting in addition to that exerted normally by the light tension spring 27. During weaving the tension exerted on the weft will be that exerted not only by the spring but also that caused by the fact that the filling in moving between the post 15 and

the element 21 will tend to clamp or draw the latter toward the post.

At the time of transfer it is customary to cut the filling at a point between the selvage and the shuttle. When the transerrer hammer not shown moves the full bobbin against the empty bobbin in the shuttle said empty bobbin is moved downwardly and tends to draw the filling still extending therefrom through the eye of the shuttle in a reverse direction. In many shuttle tensions at present in use the tension on the filling is sufficiently great so that due to the quick downward movement of the spent bobbin resulting from the transferring action the filling is broken between the tension and the bobbin. In the tension set forth herein, however, when the filling moves in a reverse direction it tends to move the tensioning element 21 away from the post 15 so that the only force acting to pinch the filling between the tensioning element and said post is that exerted by the light spring 27. As a result the weft is withdrawn from the eye in a reversed direction with reduced tendency for breaking and there is less likelihood that there will remain in the shuttle or in the shuttle box a weft end which may later be drawn into the shed to form an imperfection in the cloth.

From the foregoing it will be seen that I have provided a shuttle tension which offers more resistance to filling when moving in the normal direction than is offered when the filling moves in a reverse direction at the time of transfer. It will further be seen that by pivoting one of the tensioning elements about an axis substantially as set forth in the drawings and farther along on the path normally traversed by the filling than the cooperating fixed element is located I have provided a normally functioning snubbing action which is absent at the time of transfer when the filling tends to move in a reverse direction.

Having thus described my invention it will be seen that changes and modifications may be made therein by those skilled in the art without departing from the spirit and scope of the invention and I do not wish to be limited to the details herein disclosed, but what I claim is:

1. In a shuttle having provision for supporting a bobbin from which extends a weft end, said shuttle having a thread passage through which the weft extends, a pair of co-acting tensioning elements one of which is normally stationary with respect to the shuttle, and a pivot for the other element removed from the first named element with respect to the length of the shuttle, said second named element moving about its pivot into engagement with the first named element and being acted upon to move toward the first named element when the weft from the bobbin is moving in the normal direction through the thread passage, said second named element tending

to move away from the first named element when the weft is reversed as to its direction through the thread passage.

2. In a shuttle having provision for supporting a bobbin from which extends a weft end, said shuttle having a thread passage through which the weft extends, an upstanding post fixed with respect to the shuttle, a movable tension element to engage the post, and means defining a pivot around which the movable element may rock, said pivot being spaced from the post in the direction of the length of the shuttle, said movable tensioning element tending when the weft moves through the thread passage in the normal direction to be drawn toward the post and said movable tensioning element when the thread moves in the reverse direction moving away from the post.

29 3. In a shuttle having provision for supporting a bobbin from which extends a weft end, said shuttle having a thread passage through which the weft extends, an upstanding post fixed with respect to the shuttle, a movable tension element to engage the post, and means defining a pivot around which the movable element may rock, said pivot being spaced from the post in the direction of the length of the shuttle, said pivot also being spaced laterally from the post with respect to the width of the shuttle, said movable tensioning element tending when the weft moves through the thread passage in the normal direction to be drawn toward the post and said movable tensioning element when the thread moves in the reverse direction moving away from the post.

In testimony whereof I have hereunto affixed my signature.

40 WALTER H. WAKEFIELD.
